(57) **CLAIM**

The ornamental design for a dual compartment fluid container, as shown and described.

DESCRIPTION

FIG. 1 is a front elevation view of a dual compartment fluid container showing our new design;

FIG. 2 is a rear elevation view thereof;

FIG. 3 is a right side elevation view thereof, the opposite side being a mirror image of the shown;

FIG. 4 is a top plan view thereof, the opposite side being a mirror image of the shown; and,

FIG. 5 is an isometric view thereof.
